UNITED STATES PATENT OFFICE.

EWALD PRAEGER, OF SAN ANTONIO, TEXAS.

HOSE-SUPPORT.

1,114,033.

Specification of Letters Patent.

Patented Oct. 20, 1914.

Application filed October 18, 1912. Serial No. 726,559.

To all whom it may concern:

Be it known that I, EWALD PRAEGER, a citizen of the United States, residing at San Antonio, in the county of Bexar and State 5 of Texas, have invented a new and useful Hose-Support, of which the following is a specification.

One object of the present invention is to provide a hose support including a pivoted 10 standard having a part adapted to support the nozzle of the hose.

Another object of the invention is to provide a hose support having a pivoted standard provided at its ground engaging end 15 with means to engage the hose, whereby the standard when not in use, may be connected with the hose, to lie in parallelism with the hose.

With the foregoing and other objects in 20 view which will appear as the description proceeds the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the drawings:—Figure 1 shows in side 30 elevation one form of the invention the support being set up and in use; Fig. 2 is a bottom plan support showing the support parallel to and assembled with the hose; Fig. 3 is a perspective of the support; and Fig. 4 35 is a perspective showing a slight modification of the invention.

In carrying out the invention there is provided a bracket 1 having a projecting neck 2, terminated in a transverse shaft 3. 40 A standard is provided, the standard being pivotally connected with the bracket 1. The standard includes a loop 4, constituting a nozzle support, the arms of the loop being curved to form eyes 5 which receive the ends 45 of the shaft 3. Beyond the eyes 5, diverging arms 6 are formed, the arms 6 terminating in transverse loops 7. The arms 6 are resilient.

In practical operation, the hose 8 is placed 50 upon the bracket 1 and is secured thereto by a tie 9 of any desired form. The loops 7 are adapted to engage the ground, when the parts are positioned as shown in Fig. 1, and under such circumstances, the member 4

serves to uphold the nozzle 10. It is obvious, also, that the engagement between the member 4 and the nozzle 10 serves to prevent the standard from swinging on the shaft 3, beyond a predetermined angle.

When the occasion of the use of the support has passed by, the arms 6 may be swung into approximate parallelism with the hose 8. The free ends of the arms 6 are then pressed together and the loops 7 are engaged around the hose, the structure, under 60 such circumstances appearing as shown in Fig. 2. When the loops 7 are assembled with the hose 8 as shown in Fig. 2, the nozzle rest 4 will stand approximately at right angles to the hose. By means of the member 4, therefore, the hose may be hung up to permit the same to drain.

In that form of the invention which appears in Fig. 4, a slight modification in the bracket is shown. In Fig. 4, the bracket 11 75 is slotted as indicated at 12 and the material resulting from the formation of the slots 12 is struck downwardly to form ears 14, receiving the shaft 15, which may be a screw. The eyes 5 of the standard may engage 80 around the member 15, between the ears 14, and the part 4 being shortened.

Having thus described the invention what is claimed is:—

1. In a device of the class described, a 85 hose supporting bracket; and a two part standard pivoted to the bracket, the standard being provided at its ground engaging ends with fixed, open loops disposed at an angle to the standard, the loops acting as 90 supporting bases and as hose-engaging clips when the standard is in different positions.

2. In a device of the class described, a 95 hose supporting bracket and a standard pivoted intermediate its ends to the bracket, the standard being provided at one end with an angularly disposed nozzle rest constituting the sole means for preventing a tilting of the standard on the bracket.

3. In a device of the class described, a 100 hose supporting bracket; an angular standard pivoted intermediate its ends to the bracket, one end of the standard constituting a nozzle rest, and the other end of the standard being provided with a combined 105 hose and ground-engaging means projecting in a direction opposite to the nozzle rest.

4. In a device of the class described, a

hose supporting bracket and a standard pivoted to the bracket, the standard being provided at one end with a nozzle rest and terminating at its other end in resilient arms disposed at an angle to the nozzle rest, the arms being provided with hose engaging loops.

In testimony that I claim the foregoing as my own, I have hereto affixed my signature in the presence of two witnesses.

EWALD PRAEGER.
